UNITED STATES PATENT OFFICE.

EMIL HOTTINGER-SCHÄRER, OF HOMBRECHTIKON, SWITZERLAND.

WARPING MACHINE.

Application filed April 9, 1923. Serial No. 630,822.

To all whom it may concern:

Be it known that I, EMIL HOTTINGER-SCHÄRER, a citizen of the Republic of Switzerland, residing at Hombrechtikon, Switzerland, have invented certain new and useful Improvements in Warping Machines, of which the following is a specification, reference being had therein to the accompanying drawing.

10 It is known with warping machines to narrow the distances between the warp threads passing a broad rack provided on the bank by means of a reed which is smaller than the rack and is arranged on the warping machine. The present invention has reference to a reed for warping machines of this type which compared with known reeds presents the following advantages. The part of the reed comprising the bars or heddles can be adjusted from the flat shape into a curved or segment shape of different rises of arch. This is advantageous as the angle between adjacent threads is altered in accordance with the distance between the rack and the reed. The reed according to the invention may now be curved to such a segment shape that any friction between the threads and the bars of the reed is avoided. Furthermore a member adapted to guide the threads is arranged parallel to the frame of the reed, which member imparts an up and down movement to the threads, whereby the points in which the threads pass the reed alter constantly thus causing a smaller wear of the reed. Further two turnable stirrups are provided on the frame of the reed by means of which the crossed threads or lease between the guide reed and the reed may be formed with the aid of the lease bars.

20 The subject matter of the present invention is illustrated by way of example on the accompanying drawings, in which:

Fig. 1 shows the reed in front elevation, Fig. 2 is a horizontal section along the line II-II of Fig. 1,

Fig. 3 is a side view on a larger scale,

Fig. 4 is a vertical section along the line IV-IV of Fig. 2,

Fig. 5 shows the general arrangement of the reed in a warping machine,

Fig. 6 shows part of the reed on a larger scale,

Figs. 7, 8 and 9 illustrate the formation of the crossed threads with the reed and

Fig. 10 is a detail modification.

Referring to Fig. 5, 1 denotes the bank with the bobbins 2 the threads 3 of which pass through the rack 4. 5 is the reed arranged on the arm 6 of the warping machine and adapted to be vertically adjustable. The reed consists in a known manner of a plurality of parallel bars 7, between which stops 7^a are provided in a determined order (as is shown in Fig. 6), so that alternately two adjacent intermediate spaces are closed at an upper and a lower elevation respectively and the next two adjacent intermediate spaces are not closed by stops. The part of the reed in which the bars 7 are arranged is provided at its longitudinal sides with a flexible frame formed by rails 8, the pairs of rails 8 of the upper and of the lower side being adapted to displace themselves relatively to each other and to the bars 7 to a small extent in the longitudinal direction. The ends of the rails 8 project into recesses 9 provided in the slides 10, the latter being displaceably arranged in guide means 11 of a frame 12. Screws 13 are provided in the frame 12 by means of which a pressure may be exerted on the slides 10. These screws 13 serve to alter the distance of the slides 10 from each other. In this manner the rise α of the arch (Fig. 2) can be made of different size and such a segment shape can be given to the series bars 7 of the reed that the threads 3 pass substantially radial to the curvature given and do not rub against the bars of the reed 5. The frame rails 8 might also be connected to each other by means of pins and longitudinal slots to provide for the relative displacement of the rails. Parallel to the frame 11 of the reed a rod 15 is arranged eccentrically mounted in levers 14 and serving as a guide organ for the threads 3. The levers 14 are rotatable about pins 16 so that they can be adjusted to form a desired angle with the vertical frame of the reed. The threads 3 coming from the reed pass over the eccentrically mounted rod 15 and turn the latter by friction action. The turning rod causes the threads to perform an upward and downward movement the extreme positions of which are indicated in Fig. 4 by a full line and a dotted line respectively, so that the point in which they pass between the bars 7 is continually altered. Thereby the important advantage is

obtained that the bars are not worn out by the grinding action of the threads, as the points of contact between threads and bars alter their position continuously, thus ensuring a longer life of the bars.

Two stirrups 17 and 18 are turnably arranged about the screws 13, the stirrups serving for the formation of the lease or crossed threads 19 between the guide reed 20, which is arranged in front of the take-up roller 21, and the reed 5 by the co-operation of the known lease bars 22 and 22^a. When the warping is started all the threads 3 passing through the spaces of the reed 5 to the guide reed 20 are situated in one plane. In order to form the crossed threads 19 shown separately in Fig. 7 the lower stirrup 18 is at first turned in the upward direction into the position 18^a shown in dotted lines in Fig. 8. These threads 3 which are situated in spaces of the reed closed at the top and bottom by stops 7^a (Fig. 6) are only lifted by the turning of the stirrup 18 until they strike against said stops 7^a whereas the other threads 3^a (Figs. 6 and 8) are lifted higher. Thereby a shed is formed into which the lease bar 22^a is inserted into the position indicated in dotted lines in Fig. 8, whereupon the bar is displaced in the direction of the arrow into the position indicated in full lines in Fig. 8 and which corresponds to the position shown in Fig. 5 in which the lease bar rests in its bearings. Then the stirrup 18 is turned in the downward direction into the position shown in Fig. 9 and the upper stirrup 17 is turned into the position 17^a shown in Fig. 9. Thereby again a shed is formed however, in this case the threads 3 are lowered to the lower stops 7^a and the threads 3^a are further lowered. The lease bar 22 is now inserted into this shed in the position shown in dotted lines in Fig. 9 and is then displaced in the direction of the arrow towards the lease bar 22^a up to its bearings (Fig. 5). When the stirrup 17 is turned in the upward direction the crossed threads indicated in Fig. 7 are formed.

The pins for mounting the guide bar 15, which are eccentrically arranged in the example illustrated in Figs. 1-4, but which are in alignment may also be arranged out of alignment with axes y and z parallel to each other as is shown in Fig. 10. In this case the threads of the warp will carry out a weavy movement.

I claim:

1. A reed for warping machines, comprising a number of bars arranged at a small distance from and parallel to each other, a frame in which said bars are mounted, and adjustable means adapted to impart segment shapes of different rises of arch to said bars and thereby to the reed.

2. A reed for warping machines, comprising

a number of bars arranged at a small distance from and parallel to each other, an oblong frame having flexible longer sides in which said bars are mounted, a further frame with parts serving as guide means, slides coacting with said guide means and operatively connected to the first frame, and means adapted to alter the distance between said slides and to cause thereby the reed to curve to a segment shape of any desired rise of arch.

3. A reed for warping machines, comprising a number of bars arranged at a small distance from and parallel to each other, an oblong frame having flexible longer sides in which said bars are mounted, a further frame with parts serving as guide means, slides coacting with said guide means and operatively connected to the first frame, and screw bolts co-operating with said slides for altering the distance between the latter and to cause thereby the reed to curve to a segment shape of any desired rise of arch.

4. A reed for warping machines, comprising a number of bars arranged at a small distance from and parallel to each other, a frame in which said bars are mounted, adjustable means adapted to impart segment shapes of different rises of arch to the reed, and a guide member on the forward side of said frame for the threads passing through the reed arranged parallel to the frame and imparting an up and down movement to said threads.

5. A reed for warping machines, comprising a number of bars arranged at a small distance from and parallel to each other, a frame in which said bars are mounted, adjustable means adapted to impart segment shapes of different rises of arch to the reed, and a guide rod rotatably mounted by means of eccentrically arranged pins and rotated by the threads passing through the reed so as to impart an up and down movement to said threads.

6. A reed for warping machines, comprising a number of bars arranged at a small distance from and parallel to each other, a frame in which said bars are mounted, a second frame with parts serving as guide means, slides co-acting with said guide means and operatively connected to said first frame, means adapted to alter the distance between said slides and to cause thereby the reed to curve to a segment shape of any desired rise of arch, arms rotatably connected to said second frame and adapted to be fixed in any angular position, and a guide rod eccentrically mounted in said arms and rotated by the threads passing through the reed and imparting thereby an up and down movement to said threads.

7. In a warping machine, in combination a reed, comprising a number of bars arranged at a small distance from and paral-

lel to each other, a frame in which said bars are mounted, a second frame with parts serving as guide means, slides co-acting with said guide means and operatively connected 5 to said first frame, means adapted to alter the distance between said slides and to cause thereby the reed to curve to a segment shape of any desired rise of arch, stops alternately arranged between every two adjacent bars 10 of the reed at different elevations, stirrups turnably mounted in said second frame and adapted to form sheds on being swung into their extreme positions, and lease bars adapted to be inserted into the sheds for forming 15 crossed threads.

8. In a warping machine, a reed, a pair of parallel flexible frame rails at the top and the bottom of the reed and between which said reed is held, and means to flex said rails, 20 and thereby the reed, to arc shape.

9. A reed for warping machines, a frame, parallel guides, slides mounted between said guides, flexible frame rails mounted in said slides between the guides, a reed secured to

said flexible rails and adjusting means in the 25 frame acting on said slides to bow said rails.

10. A reed for warping machines, a frame, parallel guides, slides mounted between said guides, flexible frame rails mounted in said slides between the guides, a reed secured to 30 said flexible rails and adjusting means in the frame acting on said slides to bow said rails, and stirrups mounted on the adjusting means.

11. In a warping machine, a curved reed, 35 means to alter the curvature of the reed during the operation of the machine, a bar in front of said reed and over which the warp threads pass after leaving said reed, and pivots on which said bar is excentrically 40 mounted and rotatably and directly supported, said bar being automatically rotated by the friction of the threads as they pass over it to raise and lower the warp threads passing through the reed, for the purpose 45 described.

In testimony whereof I affix my signature.

EMIL HOTTINGER-SCHÄRER.
